(57) **CLAIM**

We claim the ornamental design for a PCR tube assembly, as shown and described.

DESCRIPTION

FIG. 1 is a perspective view of a PCR tube assembly, showing our new design;
FIG. 2 is a front elevation view thereof, the rear elevation view being identical to FIG. 2;
FIG. 3 is a left side elevation view thereof, the right side elevation view being identical to FIG. 3;
FIG. 4 is a top plan view thereof;
FIG. 5 is a bottom plan view thereof;
FIG. 6 is a perspective view of a stopper portion of the PCR tube assembly;
FIG. 7 is a front elevation view thereof, the rear elevation view being identical to FIG. 7;
FIG. 8 is a left side elevation view thereof, the right side elevation view being identical to FIG. 8;
FIG. 9 is a top plan view thereof;
FIG. 10 is a bottom plan view thereof;
FIG. 11 is a perspective view of a tube portion of the PCR tube assembly;
FIG. 12 is a front elevation view thereof, the rear, left side, and right side elevation views being identical to FIG. 12;
FIG. 13 is a top plan view thereof; and,
FIG. 14 is a bottom plan view thereof.
